[57] CLAIM

The ornamental design for a ski pole clip, substantially as shown.

DESCRIPTION

FIG. 1 is a front, top perspective view of a ski pole clip showing my new design, in the stored position; FIG. 2 is a rear, top perspective view of the side opposite that shown in FIG. 7;

FIG. 3 is a front, top perspective view in the open position;

FIG. 4 is a bottom plan view of FIG. 3;

FIG. 5 is a side elevational view taken from the right of FIG. 3, the side opposite being a mirror image thereof.
